UNITED STATES PATENT OFFICE.

LERoy A. SELL, OF PHILADELPHIA, PENNSYLVANIA, ASSIGNOR OF ONE-HALF TO MEREDITH O. SULLIVAN, OF SAME PLACE.

WIRE-STRIPPING TOOL.

SPECIFICATION forming part of Letters Patent No. 608,919, dated August 9, 1898.

Application filed July 8, 1896. Renewed January 26, 1898. Serial No. 668,082. (No model.)

To all whom it may concern:

Be it known that I, LEROY A. SELL, a citizen of the United States, residing in Philadelphia, Pennsylvania, have invented certain Improvements in Wire-Stripping Tools, of which the following is a specification.

My invention consists of a combination-tool, and relates to that class of combination-tools used by linemen and electrical-wire fitters in installation work, wiring houses, trolley-cars, &c., being especially adapted for use in any work where heavily-insulated wire is used and it is necessary to cut the insulation from the wires before the same can be joined. The tool is also adapted for making what are known as "Western Union" joints in telegraph-line wiring.

My invention is fully illustrated in the accompanying drawings, in which—

Figure 1 is a perspective view, on a reduced scale, of the improved tool. Fig. 2 is an enlarged sectional view of the jaws of the tool on the line 2 2, Fig. 1. Fig. 3 is an enlarged sectional view of said jaws on the line 3 3, Fig. 1. Fig. 4 is an enlarged sectional plan view of the lower jaw on the line 4 4, Fig. 2. Fig. 5 is a side elevation, on an enlarged scale, of the jaws of a modified form of the tool. Fig. 6 is an enlarged sectional view, on the line 6 6, of the tool shown in Fig. 5. Fig. 7 is a side elevation, on an enlarged scale, of another form of the tool. Fig. 8 is a detached perspective view, on an enlarged scale, of the knives used for transversely cutting the insulation on the wire; and Fig. 9 is a view of a modified form of cutting-knife and carrier.

In Fig. 1 I have shown the preferred form of my improved tool with all of its attachments; but it is capable of many modifications, and as I do not wish to confine myself to the precise form shown in said Fig. 1 I have illustrated in Figs. 5, 6, 7, and 9 a few of the modified forms of the improved tool, which will be more fully described hereinafter.

Referring to Fig. 1, A A represent the two jaws of the tool, which are pivoted at a and are formed integral with the handles A', by which the tool may be operated. The upper jaw carries a knife B for cutting through the insulation which covers the wires, said knife,

as shown in Fig. 1, being formed with and disposed in the center of a concave roller or drum B', which is held in the jaw by means of a set-screw b. This knife is adjustable laterally from and toward the jaw, so as to accommodate wires of varying diameter, the roller B permitting it to cut through the insulation without injuring the wire.

C is a curved guide and support for the wire while the insulation is being cut from the same, said guide being mounted on a plate c, adapted to a dovetailed groove in the lower jaw, as shown in Fig. 4, and said plate being securely held in the lower jaw by means of a set-screw c', so that it is adjustable up and down to accommodate wires of different diameters, the main reason for making the knife and wire-support adjustable being to insure the cutting of the insulation directly through the middle of the same.

D, D', and D² are knives secured to the jaws by means of suitable set-screws d, d', d², d³, and d⁴, said knives being for use in cutting the insulation on the wire transversely after it has been cut longitudinally, the insulation being then pulled from the wire by gripping it between the jaws of the tool. In Figs. 1, 5, and 8 I have shown three knives adapted to be mounted on the jaws, the knife D being fixed to the lower jaw by means of the set-screw d, the knife D' being fixed to the upper jaw, and the knife D² being adjustably mounted on the upper jaw, so as to be moved from and toward the knife D', the knives D' and D² being cut off at the corners, as shown, so as to provide an opening to accommodate the wire when the insulation is being cut.

To permit adjustment of the knife D², it is slotted at x, x', and x², and the set-screws d', d², and d⁴ are adapted to these slots. As an additional hold for the knife D' the set-screw d³ passes through the top of the same. These knives are formed with a projecting lip d⁵, which engages the reduced under side of the jaws A A, so that when the knives are cutting the strain comes on the jaws and not on the set-screws which hold the knives, the reduced portions of the jaws also serving to accommodate the insulation of the wire while it is being cut transversely. The ends of the

100

jaws are projected beyond the cutting-knife B in the form of the reduced lips A², which are useful for twisting the ends of the wire when connections are being made, and to facilitate this operation I form a hole a' in these lips A², so that a wire placed in this hole will be guided or held, as the case may require, when another wire is to be twisted around the same. Lips of similar character may be formed on the sides of the jaws of the tool, and such lateral lips I have shown at A³ in Figs. 1 and 2, the lips being provided with the grooves a³, as shown.

The arrangement of the holes in the ends of the jaws of the tool and the grooves in the laterally-projecting jaws A³, which when the jaws are closed form a hole at right angles to the hole in the jaws, make this tool particularly adapted for twisting one wire upon another. For instance, a wire to which it is desired to connect another is placed in the holes in the ends A² of the jaws, and the wire to be wrapped around it is laid in the grooves in the jaws A³ parallel to the jaws of the tool. Now if the wire passed through the holes in the ends A² of the jaws be held the tool can be turned around said wire, and the wire carried by the projecting jaws A³ will be laid around the other wire. For the purpose of holding a wire so that another wire may be laid around it I also provide the grooves a³ between the jaws of the tool at the rear of the hinge connection.

Instead of having a circular knife, as shown in Figs. 1 and 2, I may use a straight knife, as B², (shown in Figs. 5 and 6,) which is mounted in a guide E, formed integral with the upper jaw of the tool, the knife being held in place by means of a set-screw e, so that it is adjustable up and down, so as to accommodate different diameters of wire. I have shown a further modified form of this knife in Fig. 7 at B³, this knife being adapted to a guide formed integral with the upper jaw and being secured in place by a set-screw e², which passes through a slot e³, formed in the knife-blade B³.

The form of tool shown in Fig. 5 has a roller-guide E' for supporting the wire while the insulation is being cut, and in Fig. 7 I have shown a guide E', formed integral with the lower jaw. Either form may be used without departing from my invention, the main idea being to so form the guide or rest for the wire that while the insulation is being cut it will offer but little, if any, resistance in the wire as the knife is drawn along the same.

In Fig. 9 I have shown a modification of the knife, in which an arm F carries a roller for supporting the wire, and a knife F', pivoted to said arm F at f. This knife may be held in a fixed position, so as to engage the insulation on the wire by means of the thumb-screw f', carried by the free end of the same and adapted to an opening f², formed in the arm F. The full lines in Fig. 9 show the knife in its position before the wire is laid in the

support, and the dotted lines show the position the knife assumes when it is desired to cut the insulation on the wire. Such a form of tool is adapted only for the slitting of the wire, though it could be so arranged that the insulated wire could be slipped in behind the knife and against the blade, so as to cut the insulation transversely. 75

The forms of knife-blades shown in Figs. 1, 5, and 8 are preferred; but in Fig. 7 I have shown a pair of knives that may be used, these knives, however, being without the projecting under lip d⁵, which seats against the reduced portion of the jaws. These knives G are provided with half-round graduated depressions g in their cutting edges, which serve to prevent the cutting of the wire while the insulation is being cut in the same manner as the angular depression or aperture x³ in the knives D'D². These knives G are provided with the slots g', so that they may be adjusted from and toward each other to increase or diminish the apertures formed by the depressions g, and they are held in place by the set-screws g². 85

To hold the jaws together when gripping a piece of wire, especially when it is desired to turn the tool with the wire in the jaws, I provide the link H, which is connected to the handle of the lower jaw, the end of the handle being bent around the link to afford a bearing for it. This link is bent at h, and this bend is so formed that when the link is turned 100 down, as shown by dotted lines, it will be held by the handle out of the way when not in use. 95

I prefer to mount the combined roller and ripping-knife (shown in Fig. 2) and the roller-guide for the wire (shown in Fig. 6) on spindles Y, provided with shoulders y for the rear ends of the rollers and secured to said rollers by flattening the ends into the cavity y', formed in the ends of the openings in rollers, as may be readily seen on reference to the figures of the drawings above mentioned. 110

Having thus described my invention, I claim and desire to secure by Letters Patent—

1. In a tool of the character described, a wire-support, and a knife for cutting the insulation on the wire as the wire or support are moved longitudinally in relation to one another. 115

2. In a tool of the character described, a wire-support, and a knife for cutting the insulation on the same, said wire-support and knife being mounted on carriers movable from and toward each other, substantially as described. 120

3. In a tool of the character described, a wire-support and a knife for cutting the insulation on the wire, said wire-support and knife being carried by opposite members hinged together. 125

4. In a tool of the character described, a wire-support and a knife for cutting the insulation on the wire, said knife being cen-

- trally disposed with regard to the guide so as to cut through the center of the insulation, substantially as described.
5. In a tool of the character described, the combination of the wire-support, the knife for cutting the insulation longitudinally and a knife for cutting the insulation transversely, substantially as described.
6. The combination in a tool of the character described, of the wire-support, the knife for cutting the insulation longitudinally, the knife for cutting the insulation transversely, and nippers for removing the cut insulation from the wire.
- 15 7. In a tool of the character described, the combination of the upper and lower jaws hinged together, the upper jaw carrying a knife for cutting through the insulation on the wire, and the lower jaw carrying a guide for said wire while it is being cut, said knife being centrally disposed with regard to the guide so as to cut through the insulation at the center of the same.
- 25 8. In a tool of the character described, a wire-support and a knife for cutting the insulation on the wire mounted upon members hinged together, said knife being adjustable from and toward the member carrying the same, so as to accommodate wires of different 30 diameter.
- 35 9. In a tool of the character described, a wire-support, and a knife for cutting through the insulation on the wire mounted upon members hinged together, said knife and said wire-support being adjustable from and toward the members carrying the same so as to accommodate wires of different diameter.
- 40 10. In a tool of the character described, a wire-support, and a device for cutting the insulation upon the wire consisting of a circular knife formed integral with and disposed in the center of a concaved roller or drum which forms an additional guide for the wire and insures the cutting of the insulation 45 through the center of the same.
- 50 11. The combination in a tool of the character described, of the upper and lower jaws pivotally connected together, means for cutting the insulation longitudinally, and a series of knives carried by the jaws whereby the insulation may be cut transversely, substantially as described.
- 55 12. The combination in a tool of the character described, of the upper and lower jaws pivotally connected together, a reduced portion on said jaws beyond their pivotal connection, and a series of knives adapted to said reduced portion for cutting the insulation transversely, substantially as described.
- 60 13. The combination in a tool of the character described, of the upper jaw carrying a vertically-adjustable ripping-knife, and the lower jaw carrying a fixed guide for the wire.
- 65 14. In a tool of the character described, a device for cutting through the insulation on the wire and guiding the wire at the same time, consisting of a combined knife and concaved roller made in one piece, said knife and roller being mounted on a spindle adjustably secured in the upper jaw of the tool. 70
15. In a tool of the character described, means for cutting through the insulation on the wire, consisting of a combined knife and roller, and a spindle carrying the same whereby it may be mounted in the jaw of the tool, said spindle having an enlarged portion adapted to a depression in the roller whereby said roller may be held on the spindle without lateral movement, said roller having an enlarged end into which the end of the spindle may be upset so as to loosely confine the roller against the shoulder. 75
16. The combination in a tool of the character described, of the upper and lower jaws of the same, a reduced portion on said jaws, 80 a pair of knives carried by the reduced portion of the upper jaw, one of said knives being adjustable from and toward the other, and a fixed knife carried by the reduced portion of the lower jaw, said knives adapted to cut the insulation transversely. 85
17. The combination in a tool of the character described, of the upper and lower jaws of the same, a reduced portion on said jaws, and a series of knives adapted to said reduced portion, said knives being held in place by suitable set-screws, and provided with shoulders bearing against the reduced portion of the jaws whereby the strain in cutting is taken off of the set-screws, substantially as described. 90
18. The combination of the jaws of the tool, handles connected to said jaws, and a link hung to one of said handles and free to swing over the other to hold them together, said link having side legs with lateral bends whereby it can be caused to engage with and be retained in inoperative position upon the handle to which it is pivoted, substantially as described. 95
19. In wire-nippers and analogous devices, a pair of pincers having laterally-projecting jaws whereby they are adapted to grasp a wire running parallel with and alongside of the nipping-levers. 100
20. The combination in a tool of the character described, of the upper and lower jaws of the same, lips or jaws projecting laterally from the sides of the upper and lower jaws of the same, and grooves formed in said laterally-projecting jaws whereby the wire may be gripped, substantially as described. 105
- In testimony whereof I have signed my name to this specification in the presence of two subscribing witnesses.
